(57) **CLAIM**

The ornamental design for an orthopedic implant sizing device, as shown and described.

DESCRIPTION

FIG. 1 is a perspective view illustrating a first embodiment of the orthopedic implant sizing device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1–7 represent additional portions of the orthopedic implant sizing device according to the first embodiment that form no part of the claimed design.
